BY

UNITED STATES PATENT OFFICE.

AUGUST F. FROMME, OF CLEVELAND, OHIO.

DIPPING BOARD OR FRAME.

Application filed May 26, 1924. Serial No. 715,925.

To all whom it may concern:

Be it known that I, AUGUST F. FROMME, a citizen of the United States, residing at Cleveland, in the county of Cuyahoga and 5 State of Ohio, have invented certain new and useful Improvements in Dipping Boards or Frames, of which the following is a specification.

This invention is a dipping board or 10 frame designed for use in the manufacturing or molding of various rubber articles such as toy balloons etc., having for an object to provide a structure which is practically indestructible and considerably reduced in weight as compared with the 15 boards or frames used at the present time.

A further object is to provide a dipping board or frame of this character so constructed that upon assembling a set for 20 molding articles, a plurality of openings or spaces will be formed, through which heat may pass in order to speedily cure the articles.

It is likewise an object to form a dipping 25 board of cast metal which will not corrode and to fix pegs thereon in such a manner that they will not become loose and permit the molded articles to kiss or touch one another.

30 Other objects will be in part obvious and in part pointed out hereinafter.

In order that the invention and its mode 35 of operation may be readily understood by persons skilled in the art, I have in the accompanying illustrative drawings, and in the following detailed description based thereon set out one possible embodiment of the same.

Figure 1 is a plan view of a set of dipping 40 boards assembled and constructed in accordance with my invention;

Figure 2 is a bottom plan view of one of the boards;

Figure 3 is a longitudinal sectional view 45 of one of the boards or frames; and

Figure 4 is a transverse sectional view taken substantially on the line 4—4 of Figure 2.

The usual dipping board employed at the 50 present time is constructed of hard wood and carries a set of upstanding pins upon which the molds are arranged. These boards, when assembled, form a solid platform through which heat cannot pass and consequently the curing of molded articles 55 is exceedingly retarded and unsatisfactory.

The heat must necessarily pass around the opposite sides and ends of the set of boards and results in completely curing the articles at the ends of the boards prior to completion of the curing of those near the central portion, as is quite apparent. These boards are subjected to rather rough usage and quite often will split from one end to the other and loosen or possibly entirely displace a number of the mould supporting pins, thereby reducing the efficiency of operation due to the fact that a single board may be carrying only about 50 or 60% of its full capacity. These are a few of the common faults of the ordinarily constructed dipping boards which are entirely overcome through the construction hereinafter set forth.

My improved dipping board or frame 5 75 is preferably made up of cast aluminum carrying a set of spaced upstanding brass pins 6 upon which the mold members are rotatably mounted. Each dipping board or frame is widened at each end 7 and provided with a continuous depending flange 5' around its entire edge, this structure providing upon assembly, as shown in Figure 1, spaces between the boards such as will allow passage of heat into contact with the 80 articles being cured. In order to further facilitate passage of heat into contact with the articles being cured I provide each board or frame with a central longitudinal opening 8 whose longitudinal walls are connected at intervals with ribs or the like 9.

Each of the mold carrying pins 6 is tightly driven into an opening in the board 5 and is rigidly held therein thru the provision of a boss 10 integrally cast upon the 95 under side of the frame. These bosses 10 are slightly spaced from the longitudinal walls of the central opening 8 and are connected by reinforcing ribs 11 as shown in Figures 2 and 4 of the accompanying drawings. Each of the ribs 9 connecting the longitudinal walls of the central opening 8, carries a reinforcing rib which connects the adjacent bosses as shown in the bottom plan view of the drawings. This structure obviously provides a dipping board or frame 100 which is practically indestructible and of unusually light weight.

In using these boards the usual molds are arranged upon the upstanding pins and the 110 rubber articles are carried thereby for curing. These frames are set upon a support as

shown in Figure 1, and when thus assembled provide spaces 12 between the boards for the passage of heat as heretofore outlined. When removing these frames or boards, the operators usually grasp the pairs of pins or molds at the opposite ends, and where the usual construction is employed, these pins become loosened in a short time. Due to the particular mounting of these pins as heretofore outlined, this fault is entirely overcome, and the frames may be engaged with buffers in the usual manner without any undesired effects on the pins or frame.

Certain changes in the minor details of construction may be resorted to and such changes as fall within the scope of the appended claims I consider within the spirit of my invention.

I claim:

- 20 1. A dipping board consisting of an elongated flat member having its ends of greater width than its intermediate portions, and a set of upstanding mold supporting pins arranged upon the member.
- 25 2. A dipping board consisting of an elongated flat member, having a central lon-

gitudinal vertical opening therein, and a set of upstanding mold supporting pins arranged upon the member at opposite sides of the opening.

3. A dipping board consisting of an elongated flat member having a central longitudinal vertical opening, said member being of greater width at its ends than therebetween, and a set of upstanding mold supporting pins arranged upon the member at opposite sides of the openings.

4. A dipping board consisting of an elongated flat member having a central longitudinal vertical opening, the ends of said member being of greater width than the intermediate portions, a set of spaced bosses depending from the under side of said member and having vertical apertures opening through the upper side of the member, and a set of upstanding mold supporting pins having their lower ends tightly fitting in the apertures.

In testimony whereof, I affix my signature.

AUGUST F. FROMME.
